Primary Examiner — Christian P. Mclean*Assistant Examiner* — Jessica Lynn Devilbiss(74) *Attorney, Agent, or Firm* — Greenberg Traurig, LLP(57) **CLAIM**

The ornamental design for an item carrying device for a vehicle as shown and described.

DESCRIPTION

FIG. 1 is a front perspective view of my design of an item carrying device for a vehicle.

FIG. 2 is a rear perspective view thereof.

FIG. 3 is a left side elevation view thereof.

FIG. 4 is a right side elevation view thereof.

FIG. 5 is a front elevation view thereof.

FIG. 6 is a rear elevation view thereof.

FIG. 7 is a top plan view thereof; and,

FIG. 8 is a bottom view thereof.

The broken lines illustrate portions of the item carrying device for a vehicle that form no part of the claimed design.

1 Claim, 7 Drawing Sheets(56)
